UNITED STATES PATENT OFFICE.

ALBERT J. SEAMAN, OF BOSTON, MASSACHUSETTS.

Therapeutic Vibrator.

1,168,338.

Specification of Letters Patent.

Patented Jan. 18, 1916.

Application filed October 20, 1913, Serial No. 796,103. Renewed June 28, 1915. Serial No. 36,906.

To all whom it may concern:

Be it known that I, ALBERT J. SEAMAN, a citizen of the United States, residing at Boston, in the county of Suffolk and State of Massachusetts, have invented certain new and useful Improvements in Therapeutic Vibrators, of which the following is a specification, reference being had to the accompanying drawings, forming part thereof.

This invention has reference to improvements in hand operated vibrator devices used in therapeutics.

One object of the invention is to provide a simple knock down therapeutic vibrator adapted to be packed in small compass, the parts of which may be readily assembled.

Another object of the invention is to improve the construction of the vibrator head relative to its balance weight or member.

Another object of the invention is to improve the construction of the vibrator head relative to the attachment thereto of the applicator.

Other objects of the invention will appear from the following description.

The invention consists in such novel features of construction and combination of parts as shall hereinafter be more fully described and pointed out in the claim.

Figure 1, represents a side elevation of the improved vibrator parts of the same being broken away. Fig. 2, represents an enlarged sectional view of the head taken on line 2—2 Fig. 1. Fig. 3, represents a vertical sectional view of the vibrator head and related parts as taken on line 3—3 Fig. 2. Fig. 4, represents an enlarged sectional view of the operating or driving mechanism as taken on line 4—4 Fig. 1. Fig. 5, represents a sectional view taken on line 5—5 Fig. 4 showing details of the pawl and ratchet connection between the crank disk and the driving gear member.

Similar characters of reference designate corresponding parts throughout.

In the simple embodiment of this invention disclosed in the drawings the improved vibrator comprises the handle member 6 having the socket 7 adapted to be removably secured to the screw stud 8 of the drive gear casing 9 which latter has the sleeve 10 disposed diametrically to the stud 8 and adapted to removably receive the tubular post 11 having the vibrator head or casing 12 having the series of radially extending screw

threaded sockets 13, 13 and, preferably, the cover member 14.

The drive gear casing 9 has the substantially circular wall 9' and the axially disposed bearing 9'' while the open side of 60 said casing 9 is normally closed by the closure plate 15 secured to said wall 9' and having the annular wall 16 provided with the annular rack 17. Journaled in a bearing of said closure plate 15 is the driving 65 shaft 18 having at its inner end the disk 19 and having at its outer end the squared shoulder 20 adapted to receive an opening of similar shape in the crank arm 21 which latter is secured in place by the thumb 70 screw 22. Pivots mounted on the stud 23 extending from disk 19 is the pawl 24 which engages with the teeth on the periphery of hub 25 of pinion plate 26 having a series of studs 27, 27 on which are journaled 75 the pinions 28, 28 meshing with the internal teeth of rack 17 while the axially disposed spindle 29 of such plate 26 is engaged with the bearing or socket 9'' of the casing 9 and receives the bearing sleeve 30 of the large 80 bevel gear 31, the pinion teeth on said collar 30 being engaged with the pinions 28 so that the speed of the gear 31 is proportionate to the diameters of the toothed sleeve 30, the pinions 28, 28 and rack 17. 85

Journaled in the post 11 is the shaft 32 having at one end the bevel pinion 33 adapted, when said post 11 is seated in its socket 10, to engage with the bevel gear 31 while the upper end of this shaft 32 terminates in 90 the squared shoulder 34 having the stud 35. On said squared shoulder 34 is engaged the sleeve 36 of the disk rotor 37 having the weighted rim 38 which for approximately one half its circumference has the channel 39 95 whereby this rotor 37 is out of balance. On the stud 35 is pivotally mounted the arm 40 having the segmental balance weight 41 closely fitting at the inner side of the rim 38 and preferably of a size corresponding to 100 the dimensions of the channel 39 and of a weight approximating the weight of material displaced or removed by the formation of such channel. Arm 40 is secured in place by the thumb nut 42 screwed onto 105 stud 35.

The face of the rim 38 is preferably graduated as shown in Fig. 2 to facilitate the adjustment of the balance weight 41 to predetermined positions relative to the chan- 110

nel 39. With the weight 41 in the position shown in Fig. 2 the rotor 37 is approximately balanced and the rapid rotation of said rotor will not result in any material vibration of said rotor and the head or case 12 but if such weight 41 be swung around stud 35 from the position shown in said Fig. 2, said rotor will be out of balance more or less depending on the point to which said 10 weight is swung so that the rapid rotation of shaft 32 and the rotor will effect a vibration of the head or casing 12 which vibration may be transmitted therapeutically by the applicator 43 having the stem 44 screwed 15 into any one of the sockets 13, 13 of the head 12. This applicator 43 may be of any well known shape, construction and material and an assortment of such applicators all having stems 44 may be supplied with each machine.

20 Having thus described my invention I claim as new and desire to secure by Letters Patent.

A vibrator of the nature described com-

prising a drive gear case having a socket, a bevel gear rotatable in said case, means to 25 drive said gear at a high speed, a sleeve removably secured in said socket and having a vibrator head having a series of radial sockets, a shaft journaled in said sleeve and having at one end a pinion engaged with 30 said bevel gear and at the other end a square shoulder having an axial stud, a rotor rotatable within said head and having a weighted rim channeled for a portion of its circumference and an axial sleeve engaged with 35 the square shoulder of said shaft, a radial member having at its outer end a segmental balance weight to closely fit said rotor rim, said member pivotally engaged with said shaft stud, and a thumb screw engaged with 40 said stud to secure said member in adjusted position.

ALBERT J. SEAMAN.
